UNITED STATES PATENT OFFICE.

HERBERT H. STEELE, OF MARCELLUS, NEW YORK. ASSIGNOR TO THE MONARCH TYPE-WRITER COMPANY, OF SYRACUSE, NEW YORK, A CORPORATION OF NEW YORK.

TYPE-WRITING MACHINE.

1,051,925.

Specification of Letters Patent.

Patented Feb. 4, 1913.

Application filed April 9, 1910. Serial No. 554,354.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to typewriting machines and more particularly to the paper feeding and handling devices of such machines.

My invention is also applicable to other similar machines in which a paper roller and associated paper feed devices are employed, such for example as some sorts of adding machines.

The principal object of my invention is to improve the means for releasing the paper from its feed devices. This I do at least in part by moving the platen away from the feed rolls as distinguished from moving the feed rolls away from the platen. In the present instance and preferably, both devices are moved, that is to say, the feed rolls are moved away from the platen and the platen is also moved so as to leave a wider gap between the platen and feed rolls than it is convenient to produce by moving the feed rolls alone. The moving of both the feed rolls and the platen in opposite directions from their normal positions, is of especial advantage in instances where a considerable bulk of paper has to be inserted in a machine.

My invention also includes other features contributory to the main features above indicated.

My invention consists in means controlled by a finger piece or similar device for moving the platen away from the feed rolls, and also of means for moving both the feed rolls and the platen each away from the other.

My invention also consists in various features of construction and combinations and arrangements of parts all of which will be fully set forth herein and particularly pointed out in the claims.

In the accompanying drawings there is shown enough of the upper part of a typewriting machine to illustrate the application of my invention thereto. Of these drawings Figure 1 is about natural size, Figs. 2 and 3 are on an enlarged scale, and the remaining figures are on a still

larger scale. Figs. 1, 2 and 3 illustrate one form of the invention and Figs. 4 to 7 inclusive illustrate another and preferred form.

Fig. 1 is a front elevation partly in section. Fig. 2 is a side elevation partly in section. Fig. 3 is a fore and aft vertical sectional view. Fig. 4 is an end elevation partly in section. Fig. 5 is a fragmentary elevation as seen from the left. Fig. 6 is an end elevation with the parts in the released position. Fig. 7 is a front view in vertical section of the left-hand end bracket of the platen frame and with some of the associated parts. Fig. 8 is a view similar to Fig. 4 but showing a certain lever of a different form from that shown in said Fig. 4.

My invention is applicable or adaptable generally to those typewriting machines and other similar machines in which the printing is done on a roller platen and in which there are employed coöperating paper feed devices that are normally pressed against the platen.

The invention is here shown applied to a Monarch typewriter. This machine comprises the usual front strike typewriter bars and the printing keys and other devices for operating said type bars, but these parts are not shown. The machine also comprises corner posts 1 which support a top plate 2 from which rise standards 3 supporting stationary carriage rails 4 on which the main or back-bar 5 of the carriage is supported by means of rollers 6. The carriage or platen frame also comprises end brackets 7 and 8 which support the roller platen 10. The platen is provided with a shaft 11 which is journaled in two sleeves 12 that pass through the end brackets 7 and 8 of the platen frame. As ordinarily constructed heretofore these sleeves, or sleeves corresponding thereto, have been inserted in round holes in the brackets and secured in position by set screws so as to give rigid bearings for the shaft. In the present instance, however, these sleeves pass through slots 13 in the brackets 7 and 8, said slots being of the same width in a front and back direction as the sleeves, but being elongated in an up and down direction so as to admit of the sleeves being raised and lowered. In order to provide an adjustment to regulate the lower or normal position of the sleeves and of the platen, two screws 14 are thread-

ed through the brackets 7 and 8, one of them terminating in the lower part in each of the slots 13 so that the sleeves 12 normally rest on these screws, which screws can be 5 adjusted up and down. The screws 14 are provided with lock nuts 15. Each of the sleeves 12 at its inner end abuts the hub 16 on the corresponding platen head, said hub being rigidly secured to the platen shaft 10 11. At its outer end each of the sleeves 12 abuts the end of the hub 17 of the finger wheel 18, these hubs also being rigidly mounted on the shaft. The construction is such that the shaft is free to turn in the sleeves 12 15 but is incapable of endwise motion with relation to said sleeves. In order to prevent endwise motion of the sleeves themselves, each of them is formed with an annular enlargement 20 which bears against the outer 20 surface of the associated bracket 7 or 8.

Referring now more particularly to Figs. 1, 2 and 3, the means for moving the platen up and down comprises two crank arms 21, one of said crank arms being rigidly mounted 25 ed on each of the sleeves 12 just outside the enlargement 20. As this mechanism is alike at both ends of the platen, it can be understood by reference to Fig. 2, which shows the mechanism at the left-hand end of the 30 platen. It will be seen that the crank arm 21 is pivoted at 22 to a link 23 which, as shown in Fig. 1, is pivoted on the reduced outer end of a collar 24 that is mounted on a screw 25, which screw passes loosely 35 through a lug or bracket 26 projecting upward from the end bracket 7 of the carriage. Said screw 25 is threaded into the end of a frame rod 27 which is formed at each of its ends, as shown at its right-hand end in 40 Fig. 1, with a tongue 28 that engages in a cross-groove in the bracket 26 to prevent any turning of the rod 27. This rod 27, mounted substantially as shown, is a part of the ordinary construction of the Monarch machine where it is utilized to support certain paper fingers which are not shown in Figs. 1, 2 and 3 but which are shown in Figs. 4 and 6 of the drawing. In Fig. 1 this rod is 45 shown cut out at 30 in order to admit of a sufficient elevation of the platen. In order 50 to provide an adjustment for the link 23 the reduced end of the collar 24 may be made eccentric of the screw 25 and this collar may be of prismatic form externally, as shown 55 at the right-hand end of Fig. 1, so that it can be turned with a wrench. Normally the centers of the screw 25 and the pivot 22 and the shaft 11 are approximately on a straight line as shown in Fig. 2. When it 60 is desired to raise the platen the toggle thus formed is broken to the position shown in Fig. 3 which obviously draws the platen upward, the sleeves 12 sliding in the slots 13. When the screws 14 are suitably ad- 65 justed and the parts stand in the position

of Fig. 2 the link 23 can be adjusted toward and from the platen shaft by loosening the screw 25 and turning the sleeve 24. The parts can be secured in adjusted position by then holding the sleeve 24 and tightening the screw 25. When this screw is tightened it holds the rod 27 firmly in position and the head of the screw presses the sleeve 24 firmly against the lug 26, thus holding said sleeve in adjusted position. The head of the screw also overlaps the link 23 and thus retains said link in position on the sleeve 24. The link 23 is of angular formation as shown in Fig. 2, said link being pivoted at 31 to a floating hand lever or link 32 having a paper release handle or finger piece 33 formed thereon. Below the point 31 said link 32 is pivoted at 34 to a crank arm 35 which is capable of turning about a center 36. The handle 33 normally occupies the rear position shown in Fig. 2 and the platen is lifted by drawing said handle toward the front until it is arrested by the lug 26 or by some of the associated parts as shown in Fig. 3. This breaks the toggle 21, 23 and raises the 90 platen. Meanwhile it brings the points 25, 31 and 34 to a dead center relation.

The machine is equipped with the usual Monarch rear feed rolls 37 and forward feed rolls 38. The rolls 37 are mounted on a 95 shaft or rod 40 carried by arms 41 which are pivoted at 42 in lugs 43 projecting from the back-bar 5 of the carriage, and said rolls are pressed toward the platen by springs 44. The forward rolls 38 are carried by a rod 100 45 which in turn is carried by arms 46 which are pivoted at 47 in the brackets 43, said arms 46 being pressed toward the platen by springs 48. The machine is also equipped with a paper apron 50 which is 105 hung on the rod 36 above referred to as constituting the center about which the arms 35 turn. The forward part of the paper apron is held up by plate springs 51 mounted on the arms 46. A front scale plate 52 is 110 provided, said scale plate being pivoted at 53 to arms 54, Fig. 2, projecting toward the front of the machine from the back-bar 5 of the carriage. This scale plate is connected with the arms 41 by means of a link 115 55, best shown in Fig. 3. These parts have not been minutely shown or described for the reason that they are or may be of substantially the ordinary Monarch construction which is well known in the art. 120

The mechanism already described constitutes a paper feed release mechanism sufficient for ordinary purposes, it being only necessary to provide suitable means for preventing the feed rolls 37 and 38 and their 125 associated devices from following the platen in its upward movement. These feed rolls may also be moved down to increase the space for the insertion of the paper, and this can obviously be done by independent means 130

and by a separate operation. I prefer, however, to drop these feed rolls down by the same movement of the handle 33 that elevates the platen, thus leaving between the 5 platen and the other feed devices about double the usual space for the insertion of an especially thick pile of papers. To this end the arm 35 is rigidly mounted on the end of the rod 36 which rod is in fact the ordinary 10 paper feed release rod heretofore employed in the Monarch machine. Each end of this rod projects outside of the end bracket of the carriage where it is formed with a reduced part 56, Fig. 2, of non-circular out- 15 line, on which the arm 35 is seated and where said arm is secured in place by a screw 57 threaded into the end of the rod. Each of the arms 35 is formed with a lug 58 which normally contacts with a pin 60 20 projecting from the carriage bracket to determine the normal position of the parts. The rod 36 has projecting therefrom lugs 61, Fig. 3, which, when the rod is rocked by the operation of the finger piece 33, press 25 down the posts 62, projecting from the arms 41, which carry the feed rolls 37, so that, when the finger piece is pulled forward, these arms are depressed to move said feed rolls away from the platen. The forward 30 ends of the arms 41 press down the arms 46, thus depressing the feed rolls 38, and the paper apron 50 drops down with said arms 46. The motion of the arms 41, acting through the links 55, also rocks the scale 35 plate 52 about its pivot, thus deflecting the scale plate from the surface of the platen. In Fig. 3 the normal position of the platen is indicated by the broken line 63 and the normal position of the feed rolls 37 and 38 40 are indicated respectively by the lines 64 and 65. It will be seen that when the handle 33 is pulled forward the platen moves upward and the other parts move downward both away from their normal positions, thus 45 leaving an unusually wide space between the platen and the coöperating paper handling devices.

The platen at its left-hand end has a line space wheel 66 with which coöperates the 50 usual line spacing devices, which devices, however, are not shown in the present instance. This wheel is also engaged by a detent roller 67, Fig. 2, which is journaled in the end of an arm 68 which is in the nature 55 of a plate spring that presses the roller 67 against the teeth of the wheel 66. This roller stands approximately directly above the platen shaft so that when the platen is moved up and down by the devices de- 60 scribed, the teeth of the wheel 66 slide up and down on the roller 67 without turning the platen.

In case the platen is a short one and consequently not a heavy one the friction of the 65 parts may be sufficient to hold the platen in

its elevated position shown in Fig. 3, this being especially so as the links 28 and 32 constitute a toggle which in the position of Fig. 3 is straight. The arm 35 is pressed upward by the tension of all of the several 70 springs which control the paper feed rolls. If, however, the platen be long and heavy, it may be necessary, and in any event it may be preferable, to provide additional means for sustaining the platen in its elevated po- 75 sition. The means shown for this purpose in Figs. 1 and 2 consists of a wire spring 70 coiled about a post 71 projecting from the end bracket of the carriage. Two of these supporting springs are shown one at 80 each end of the platen. The post 71 is here shown as a screw threaded into the carriage end and projecting a suitable distance therefrom. The spring 70 is preferably coiled a number of times around the post 71 and its 85 rear end is bent so as to project through a hole 72 in the arm 35, the other end of the spring projecting forward and lying beneath the sleeve 12. The tension of this spring is exerted upward on both the parts 90 12 and 35. This spring constitutes in effect an elastic or resilient lever of the first order pivoted at 71. In the position shown in Fig. 2 the forward end of this spring lever is operating against the toggle 21, 23 which 95 toggle is at, or a trifle past, the dead center; whereas the rear end of it is worked against the toggle 23, 32 which toggle is broken. The spring therefore operates to hold the handle 33 in its rear position. When the 100 parts assume the position of Fig. 3 the rear end of the spring is worked against a straight toggle and therefore is firmly held down, and the tension of the spring is sufficient to support the weight of the platen on 105 the forward arm thereof. This lever is made as a spring for the reason that, although the sleeve 12 moves up when the arm 35 moves down, the relative motions of these two parts are not uniform. When the handle 33 first 110 begins to move forward the arm 35 moves down comparatively rapidly whereas the sleeve 12 moves upward but little. In the latter part of the forward motion of the handle 33 the toggle 23, 32 is approaching 115 a dead center and the arm 35 is moving down but slowly whereas the toggle 21, 23 is broken and the sleeve 12 is moving upwardly comparatively rapidly. The elasticity of the lever 70 compensates for these 120 varying inequalities of motion. In the form of the invention shown in Figs. 1, 2 and 3 no paper fingers are employed above the printing line, their place being taken by the M-shaped paper guide 73 which is secured 125 at 74 to the stationary frame-work of the machine. This paper guide is of a sort com- monly used on the Monarch machine.

In the form of the invention shown in 130 Figs. 1, 2 and 3 the only connection between

the linkages at the two ends of the platen consists of the rod 36. If only one of the handles 33 is operated this rod will operate the other handle to certain extent but will not impart a complete operation to it. This is for the reason that in the latter part of the motion of the handle 33 the links 23, 32 are approaching the dead center position and the weight of the platen, which comes on the link 23 in the latter part of the motion, offers very substantial resistance to the straightening of this toggle. It is impossible to straighten a toggle entirely against a substantial resistance by pulling between the two ends of the toggle. For this reason it is necessary in this form of the invention to have one of the handles 33 at each end of the platen and to operate both of them.

20 In the form of the invention shown in Figs. 4 to 7 inclusive, an additional connection is provided between the linkages at the two ends of the platen so as to admit of completely operating the mechanism by the manipulation of one handle. In that part of the stroke of the handle at which the toggle 23, 32 is approaching the dead center the other toggle 23, 21 is broken. If therefore a connection be provided between the two links 23 this connection will be able to complete the part of the operation at the far end of the platen that the rod 36 was unable to complete. In the form of the invention shown in the last sheet of drawings, therefore, the links 23 are rigidly mounted on the rod 27 and this rod is arranged to be turned in the lugs 26. In Figs. 4 to 7 inclusive I have designated most of the corresponding parts by the same reference numerals as in the other figures of the drawing, notwithstanding the fact that some of these parts differ somewhat in construction, such for example as the rod 27 which in this instance is rotatable instead of fixed. In this form of the invention the paper feed devices associated with the lower part of the platen are or may be the same as in the other form and these parts have accordingly not been shown as fully as in the other figures. The lugs 26 are shown higher so as to admit of the desired elevation of the platen without interfering with the rod 27 and with the paper fingers and other devices which, in these figures of the drawing, are shown mounted on said rod. The lugs 26 are also made larger so as to admit of the full size of the rod 27 passing through said lug as shown in Fig. 7. On the outside of the lug 26 the rod 27 is reduced forming a shoulder 75 and the eccentric bearing collar 24 is mounted on said reduced portion. The extreme end of the shaft 27 is flattened off as shown at 76, Figs. 4 and 7, and an arm 77 is fitted over said extreme end of the rod 27 and said arm carries a pin 78 which is shouldered, headed and riveted up, as shown in Fig. 7. This pin is adapted to play in a slot 80 formed in the link 23 in the direction of a line joining the rod 27 and the pivot 22. The link 23 is mounted on a reduced part 81 of the collar 24, this part being eccentric to the rod 27 as shown in Fig. 5. When the screw 25 is tight, the plate or arm 77 and the collar 24 are tightly clamped between the head of said screw and the shoulder 75 on the end of the rod 27, so that the collar 24 is not free to turn with relation to the rod. The plate or arm 77 necessarily turns with the rod 27 on account of the flattened part 76, and the link 23 is constrained to turn with this plate by reason of the pin and slot connection 78 and 80. The link 23 can be adjusted toward and from the platen shaft by loosening the screw 25 and turning the collar 24 with a wrench, the slot 80 allowing the link 23 to move radially of the rod 27. When the parts are properly adjusted the screw 25 is tightened. The construction is such that when the link 23 is operated by the handle 33, the rod 27 turns with it and if only one handle 33 is operated said rod 27 communicates the motion of one of said links 23 to the corresponding link at the other end of the platen. As the two arms 35 are rigidly mounted on the rock shaft 26, they also are constrained to turn in unison. In this form of the invention therefore it is not necessary to operate but one of the handles 33 and in fact it is not necessary to provide but one such handle. In Fig. 4 the parts are shown in normal position and in Fig. 6 in their released position. It will be seen that in all essential respects the release is effected in the same way as in the other form of the invention with the exception above noted that it can be done by manipulation of a single handle. In this respect this form of the invention is preferable to the other. In connection with this form of the invention I have also shown the usual Monarch erasing plate 82 mounted on the rod 27. As this plate is freely pivoted on said rod its free edge engages the platen in both the upper and lower position thereof. I have also shown mounted on the rod 27 the usual adjustable paper fingers for guiding the paper after it has passed the printing line. With one exception which will be noted, these devices are identical with those heretofore employed in the Monarch machine. They comprise rigid arms 83 which are so mounted on the rod 27 that they can be adjusted lengthwise of said rod but are held against turning with relation to the rod. The result is that when the parts are in the normal position shown in Fig. 4 these paper fingers are down in their usual operative position whereas when the rod 27 is rocked in the act of releasing the paper handling devices, the paper fingers are also elevated as shown in Fig. 6 so that they

also are released from their usual coöperation with the platen. The paper finger devices comprise small feed rolls 84 which are mounted in arms 85 pivoted at 86 to the free ends of the arms 83. They also comprise spring arms 87 projecting forward and downward from supports 88 made of sheet metal and having ears 90 bent up, one on either side of the arm 83, to which said ears are pivoted at 91. The parts 88 are pressed toward the platen by compression springs 92 each situated between the arm 83 and part 88. The only modification that I have made in these paper finger devices consists in the addition thereto of a stop screw 93 which is threaded through the arm 83 and at its lower end is adapted to contact with the rear end of the part 88. When the paper fingers are elevated as shown in Fig. 6 the spring arms 87 would turn too far about their pivots 91 and drop down against the platen. These stop screws are put in to prevent this dropping down of said arms.

It will of course be understood that the erasing plate and the paper fingers can be used on the form of invention shown in Figs. 1, 2 and 3 by suitably elevating the rod 27 so as to give room for them.

The spring supporting lever 70 can be employed in connection with the form of the invention shown in Figs. 4-7, and in Fig. 8 I have shown such a lever used in connection with mechanism identical in other respects with that of said Figs. 4-7. In said Figs. 4-7 I have, however, shown a modification of this supporting device which consists of a lever 94 pivoted to one of the brackets 7, 8 on a screw 95, the forward end of the lever lying beneath the sleeve 12 or the enlargement 20 thereof. The rear arm of the lever has a lug 96 bent outward therefrom and lying beneath the crank arm 35. Comparatively speaking, the lever 94 is a rigid lever and is incapable of the compensating flexure referred to in describing the lever 70 or at least this lever is incapable of any such extent of flexure as the lever 70. In order to enable me to use this comparatively rigid lever the pivot thereof is put much nearer to the rear than to the front end of the lever, so that the forward lever arm is considerably longer than the rear lever arm, and the rear arm of the lever, when the parts are in their normal position shown in Fig. 4, is not in contact with the arm 35, there being considerable lost motion between said arm and the lug 96. In order to keep the lever from dropping down too far in this position it is provided with an arm 97 that contacts with a stop pin 98. In the latter part of the downward motion of the arm 35 said arm depresses the lug 96 and elevates the forward arm of the lever 94, bringing it up to the position shown in Fig. 6. During

this part of the motion the sleeve 12 is moving upward much more rapidly than the arm 35 is moving downward and hence the necessity for making the forward arm of the lever longer than the rear arm. Even with this compensation this lever operates by springing the parts to some extent but it is so designed that this springing of the parts is not excessive. This lever constitutes a more positive and rigid holding device than the lever 70 for holding the platen in its upper position. In order to provide for an adjustment of this lever it is formed with a cut-out 100 which admits of the lever being bent with pliers.

It will of course be understood that various changes other than those specifically described, can be made in the details of construction and arrangement without departing from my invention.

What I claim as new and desire to secure by Letters Patent, is:—

1. In a typewriting machine, the combination of a platen, paper feed devices coöperating with said platen, and means for moving said platen away from said paper feed devices and for moving said paper feed devices away from said platen simultaneously by a single release movement.

2. In a typewriting machine, the combination of a rotary platen, a paper feed device coöperating with said platen, and a paper feed release key connected to move both said platen and said paper feed devices to releasing positions.

3. In a typewriting machine, the combination of a rotary platen, a coöperating paper feed roller, and means for simultaneously moving said platen and said roller each with relation to the other, to releasing positions.

4. In a typewriting machine, the combination of a platen, paper feed devices coöperating with said platen, key actuated means normally holding said platen in coöperative relation with said paper feed devices but capable of actuation to move said platen away from said paper feed devices, and adjustable stops for positively arresting the platen in its motion toward said paper feed devices.

5. In a typewriting machine, the combination of a platen, paper feed devices coöperating with said platen, paper feed release mechanism including means for moving said platen away from said paper feed devices for the purpose of inserting or adjusting the paper, and means acting substantially to hold the platen against rotary motion during such movement.

6. In a typewriting machine, the combination of a platen frame, a roller platen mounted in said platen frame with provision for motion transverse to its axis, paper feed devices coöperating with said platen

in its normal position, two toggles, one at each end of the platen, said toggles when straight holding said platen in position to coöperate with said paper feed devices and 5 when broken moving said platen away from said paper feed devices, and adjustable stops for determining the normal position of the platen.

7. In a typewriting machine, the combination of a platen frame, a roller platen mounted in said platen frame with provision for motion transverse to its axis, paper feed devices coöoperative with said platen in its normal position, two toggles, one at each 10 end of the platen, said toggles when straight holding said platen in normal position when with said paper feed devices and when broken moving said platen away from said paper feed devices, adjustable stops for determining the normal position of the platen, means for causing the two toggles to work in unison, and a handle for operating said toggles.

8. In a typewriting machine, the combination of a platen frame, a roller platen mounted in said frame with provision for motion transversely of its axis, a toggle for having said platen in normal position when the toggle is straight and for moving said 25 platen with relation to the platen frame when the toggle is broken, and an eccentrically mounted pivot for one end of said toggle, said pivot being adjustable by turning it to vary the pivotal center of that end of the toggle.

9. In a typewriting machine, the combination of a platen frame, a roller platen mounted in said frame with provision for motion transversely of its axis, a toggle for holding said platen in its normal position 30 when the toggle is straight and the raising said platen to an abnormal position when the toggle is broken, and a lock or retaining device for holding said platen in its raised position.

10. A platen and feed rolls coöoperating with the underside of the platen, said platen and feed rolls both being constructed and mounted for movement away from each 40 other to facilitate insertion of paper, combined with a release device for simultaneously moving said platen and feed rolls and means acting substantially to hold the platen against rotary motion during such movement.

11. In a typewriting machine, the combination of a platen, paper feed devices coöoperating with said platen, means for moving said platen away from said paper feed 50 devices, and means for moving said paper feed devices away from said platen, the two said means being connected so that they operate together.

12. In a typewriting machine, the combination of a platen, paper feed devices co-

operating with said platen, and a hand operated device connected both with said platen and with said paper feed devices and acting when operated to move both the platen and the paper feed devices each away 70 from the other.

13. In a typewriting machine, the combination of a platen, paper feed devices coöoperating with said platen, means including a hand operated toggle for moving said paper feed devices away from the platen, and means including a hand operated toggle for moving said platen away from said paper feed devices, the two said toggles having one member in common so that they are 80 operated together.

14. In a typewriting machine, the combination of a platen, paper feed devices coöoperating with said platen, a hand operated toggle at each end of the platen for moving said paper feed devices away from said platen, a hand operated toggle at each end of the platen for moving said platen away from said paper feed devices, the two toggles at each end of the platen having a 90 member in common, and means connecting the toggles at the two ends of the platen so that all of said toggles are operated together.

15. In a typewriting machine, the combination of a platen, paper feed devices coöoperating with said platen below the writing line, paper feed devices coöperating with said platen above the writing line, a handle, and paper feed releasing mechanism including means for moving the lower paper feed devices downward, means for moving the platen upward, and means for lifting the upper paper feed devices away from the platen, the three last recited means 100 being all operated by said handle.

16. In a typewriting machine, the combination of a platen, paper feed devices coöoperating with the platen below the writing line, a rod lying above the platen, devices 110 connected with said rod for lifting the platen away from said paper feed devices, and paper fingers mounted on said rod and lifted away from the platen by the operation of said devices.

17. In a typewriting machine, the combination of a platen, paper feed devices coöoperating with said platen, paper feed releasing mechanism including a toggle at each end of the platen for moving said 120 paper feed devices away from the platen, and a toggle at each end of the platen for moving the platen away from the paper feed devices, the two toggles at each end of the platen having a member in common, and two connections between the toggles at the two ends of the platen.

18. In a typewriting machine, the combination of a platen frame, a roller platen mounted in said frame, a crown ratchet 130

wheel connected with said platen, a detent engaging said ratchet wheel, and means for moving said platen with relation to said platen frame substantially in the direction 5 of the radius through said detent so that the platen is not rotated when it is moved.

19. In a typewriting machine, the combination of a platen, paper feed devices co-operating with said platen, and a hand operated toggle for moving said paper feed devices away from said platen, a hand operated toggle for moving said platen away from said paper feed devices, the two said 10 toggles having a member in common, and a spring lever acting on both of said toggles to maintain them either in their normal or in their operated position.

20. In a typewriting machine, the combination of a platen, a platen frame, a rod extending lengthwise of said platen frame with freedom to turn therein, means connecting each end of said rod with the corresponding end of said platen for imparting to said platen a motion of translation with 25 relation to said platen frame, said means at each end of the platen comprising a collar.

capable of adjustment on said rod by turning it around the rod, an arm eccentrically mounted on said collar, a second arm mounted on said shaft without freedom to turn, 30 and a slide connection between the two arms whereby the relation of the platen to the rod can be adjusted.

21. In a typewriting machine, the combination of a platen, a paper finger comprising an arm having a paper controlling device pivoted thereto and spring-pressed toward the platen, means for lifting said arm away from the platen, and an adjustable device for limiting the motion of said paper 35 controlling device about its pivot so as to cause said paper controlling device to be lifted away from the platen when the arm is moved.

Signed at Syracuse, in the county of 45
Onondaga and State of New York this 7th
day of April A. D. 1910.

HERBERT H. STEELE.
